Inventor:
Ananias Swartz,
By James L. Norris,
Atty,

UNITED STATES PATENT OFFICE.

ANANIAS SWARTZ, OF ST. LUKE, VIRGINIA.

DESIGN FOR A WIRE TIGHTENER OR STRETCHER.

SPECIFICATION forming part of Design No. 34,218, dated March 12, 1901.

Application filed February 15, 1901. Serial No. 47,517. Term of patent 14 years.

To all whom it may concern:

Be it known that I, ANANIAS SWARTZ, a citizen of the United States, residing at St. Luke, in the county of Shenandoah and State of Virginia, have invented and produced a new and original Design for a Wire Tightener or Stretcher, of which the following is a specification.

My invention relates to a new and original design for wire tighteners or stretchers, and is illustrated in the accompanying drawings, in which—

Figure 1 is a perspective view, and Fig. 2 a side elevation. Fig. 3 is a view looking at one side of the wire tightener or stretcher, and Fig. 4 a view looking at the opposite side thereof.

The leading features of my invention reside in a wire tightener or stretcher having a cylindrical hub from which intermediate its ends radiate arms the ends of which are connected by a segment formed with a series of peripherally-laterally-projecting teeth, the hub at one side of the arms being formed with a recess extending inwardly from the end of the hub, providing separated fingers having perforations, and the hub between said fingers and the radial arms being formed with a perforation, said hub at the other side of the arms being cylindrical throughout a part adjacent the arms and having a transverse aperture therethrough and its end of angular formation.

In the said drawings the reference-numeral 1 indicates the wire tightener or stretcher, 35 composed of a hub 2, from which intermediate its ends project radial arms 3, the ends of which are connected by a segment 4, formed with peripheral laterally-extending teeth 5.

The numeral 6 indicates a recess extending 40 inward from the end of the hub, providing separated fingers 7.

8 indicates the perforation through the fingers and 9 the perforation through the hub between said fingers and the radial arms. 45

The numeral 10 indicates the transverse perforation in the cylindrical part of the hub at the side opposite the fingers 7, and 11 indicates the squared end of the hub.

My design presents a wire tightener or 50 stretcher of novel, pleasing, and distinguished appearance.

Having thus described my invention, what I claim is—

The design for a wire tightener or stretcher, 55 substantially as herein shown and described.

In testimony whereof I have hereunto set my hand in presence of two subscribing witnesses.

ANANIAS SWARTZ.
